RICHARD CHRISTOPHER WILLIAMS AND WALTER DE CHÈRE, OF TORONTO, ONTARIO,
CANADA.

FLY SCREEN.

Application filed September 29, 1923. Serial No. 665,640.

To all whom it may concern:

Be it known that we, RICHARD CHRISTOPHER WILLIAMS and WALTER DE CHÈRE, both subjects of the King of Great Britain, and both residents of the city of Toronto, in the county of York, in the Province of Ontario, Canada, have invented certain new and useful Improvements in Fly Screens, of which the following is the specification.

Our invention relates to improvements in fly screens and the object of the invention is to devise a screen which will be carried automatically in and out of position in the window opening by the raising and lowering of the window sash and in which simple means are provided for locking the fly screen roll in any position in which it may be wound and in which detachable means are provided for securing the free edge of the fly screen to the window sash and it consists essentially of the arrangement and construction of parts as hereinafter more particularly explained.

Fig. 1 is a perspective view of a window and our screen showing the window sill broken away to exhibit the fly screen roll.

Fig. 2 is a similar view to Figure 1 showing the fly screen detachably connected to the lower sash of a window.

Fig. 3 is a vertical section through the lower portion of Figure 1.

Fig. 4 is an enlarged perspective detail of the fly screen roll and its housing.

Fig. 5 is a longitudinal sectional view through the housing shown in Figure 4.

Fig. 6 is a vertical section on the line 6-6 Figure 5.

Fig. 7 is a plan detail view of a means for detachably connecting the end of the fly screen to the window sash, and

Fig. 8 is a longitudinal sectional view through Figure 7.

Fig. 9 indicates an alternative structure.

In the drawings like characters of reference indicate the corresponding parts in each figure.

1 indicates a window frame or casing in which is slidably supported in the usual manner a sash 2. 3 is the window sill. 4 is a cross slot formed in the frame immediately to the outside of the sill 3. The lower portion of the window frame 1 is formed hollow as indicated at 1^x. 5 is a housing which is suitably supported within the portion 1^x so as to extend crosswise of the window. The housing 5 is preferably formed

in two portions 5^x and 5° telescopically connected together as indicated at 6. The member 5^x is provided with a tongue 6^x fitting into edge grooves 7 formed at each edge of the member 5°. By this means the members 5^x and 5° may be drawn longitudinally apart to the extent desired to fit the width of the window. The housing 5 in proximity to one end is provided with a slot 8 for the purpose which will hereinafter appear. 65

9 is a spring roller. 10 is a pintle formed at one end of the roller 9, such pintle being journalled in an orifice 11 formed in one end wall of the housing 5. The roller 9 is divided into two portions 9^x and 9° telescopically connected together as indicated at 12. 13 is a block secured within the member 9° in proximity to its inner end. The block 13 is provided with a central recess 13^x. 14 is a wall formed in the member 9° in proximity to its outer end, such wall being provided with a central orifice 14°. 15 is a rod provided with a reduced inner end 15^x journalled in the recess 13^x, the outer end of the rod 15 is journalled in the orifice 14° and is 80 provided with a rectangular extension 16 projecting outward so as to extend into close proximity to the adjacent end wall of the housing 5. 75

It will be noted on referring to Figure 5 85 that an interspace is left between one end of the roll 9 and the corresponding end of the housing 5. 17 is a locking plate which is preferably circular in form and provided with a handle 18 extending through the slot 8 of the housing 5. The plate 17 is provided with a horizontal slot 19 through which the rectangular extension 16 extends, such extension fitting the slot so as to prevent rotary motion therein. 20 is a tongue which is 90 stamped inwardly from the plate 17 and 21 is a projection carried by the end of the roller 9. 22 is a spiral spring surrounding the rod 15, such spring being secured at its inner end to the block 13 and at its outer end to the 100 outer end of the rod 15. 23 is a strip of wire mesh forming the fly screen proper, the strip 23 being secured to the roll 9 and normally wound thereon. By unwinding the fly screen strip from the roll the spring 22 is 105 drawn into tension in a similar manner as occurs when a window blind is rolled. 24 are pins carried preferably upon the window sill 3, the pins 14 being provided with annular grooves 25 and heads 26. 27 are de- 110

tachable securing devices. The devices 27 are hingedly connected to an edge strip 28 secured along the free edge of the fly screen 23.

5 As will be noted on referring to Figure 8 the devices 27 each comprise a plate 28* having an orifice 29 extending from one face thereof and a recess 30 formed in the other face around the orifice 29. 31 is a plate 10 covering the recess 30, such plate being provided with an orifice 32 in alignment with the orifice 29.

33 and 34 are spring fingers, the ends 36 thereof being connected together and to the 15 plate 30, the opposite ends of the fingers being free. Intermediately of their length the fingers 34 and 35 are provided with opposing concaved portions 39 and 40 located in a concentric position to the orifices 29 and 20 32. 41 are pins secured to the window sash 2 in alignment with the pins 24 and similarly constructed to the pins 24.

When it is desired to use the fly screen the lower edge of the window sash 2 is carried 25 into an adjacent position to the free edge of the fly screen, the devices 27 being then thrown upward into position so that the heads of the pins 41 extend through the orifices 29 and 32, and the concaved portions 30 of the fingers 33 and 34 engage the annular groove corresponding to the annular groove 25 of the pin 24. By this means the fly screen is connected to the sash 2 and by raising the sash 2 the screen is drawn upward 35 from the spring roller 9, thereby covering the opening formed by the raising of the window. When it is desired to detach the fly screen from the window sash all that is necessary to do is to swing the devices 27 40 on their hinge pins out of engagement with the pins 41, the fingers 34 and 35 springing apart as the pull is exerted, thereby freeing the fly screen from the window sash. The fly screen is then lowered and as it is lowered to 45 its final position the devices 27 are swung outward so as to engage the pins 24 in a similar manner to that described in connection with the pins 41.

In order to lock the spring roll from 50 being turned and thereby prevent the raising of the window from the outside, we force the handle 18 inward so as to carry the projection 20 into the path of the projection 21. It will thus be seen that as the roll 55 9 is turned these projections will come into engagement, thereby preventing the further turning movement of the roll and also thereby preventing the raising of the window sash further. Also when the housing 5 is removed 60 from the window casing as may be done at the end of the season, the plate 17 is moved into the locking position so as to hold the spring 15 in tension, preventing the fly screen running slack. If desired, the 65 housing 5 and the fly screen contained there-

in may be secured on the outside of the window sill across the bottom of the window and the pins 34 carried thereby. By this means our fly screen may be adapted to an old window instead of being built into the 70 structure when the window frame is made as illustrated in Fig. 9.

In order to prevent the flies from creeping around the vertical edges of the fly screen we have provided metal strips 42 carried by the window frame so as to bear upon the face of the fly screen adjacent to each edge thereof, as is clearly indicated in Figure 2, thus sealing the edge.

From this description it will be seen that 80 we have devised a very simple form of fly screen which is automatically carried in and out of its operative position by the raising and lowering of the window sash and in which simple means are provided for locking the fly screen in the stationary position either when completely rolled in the housing 85 5 or partially unwound therefrom, and also simple means for detachably connecting the free edge of the fly screen to the window 90 sash.

What we claim as our invention is:

1. In a fly screen, the combination with a spring roller having a flattened pintle at one end, a housing for the roller provided 95 with a peripheral slot, a plate fitting against the end of the roller and having a longitudinal slot through which the flattened pintle extends, a handle extending outwardly from the plate through the slot of the housing, a 100 projection extending inwardly from the diametrically opposite side of the plate to the handle and a projection extending from the roller adapted to engage the projection of the plate when the projection of the 105 plate is moved into circumferential alignment therewith.

2. In a fly screen, the combination with a spring roller mounted in suitable bearings, a fly screen strip wound upon the roller and window sash attaching means comprising headed projections extending from the sash of the window, and headed projections extending from the sill, arms hinged to the free end of the fly screen provided with 115 orifices extending therethrough and into which the heads of the sash are adapted to extend when the member is swung in one direction and into which the heads of the orifices of the sill are adapted to extend 120 when the member is swung in the opposite direction, spring finger means carried by the hinge member adjacent the orifice and adapted to engage beneath the head of either the sash or the sill when either the 125 head of the projection of the sash or the head of the projection of the sill is in entering position within the orifice.

RICHARD CHRISTOPHER WILLIAMS.
WALTER DE CHÈRE.
